WAVE-SIGNAL TRANSLATING APPARATUS
CHASSISDonald H. Mitchell, Chicago, Ill., assignor to
Motorola, Inc., a corporation of Illinois

Application May 30, 1945, Serial No. 596,783

2 Claims. (Cl. 173—328)

1

This invention relates to wave-signal translating apparatus chassis which is substantially free from bonded circuit connections and, while it is of general application, it is particularly suitable for embodiment in low-cost radio broadcast receivers adapted to be manufactured in large volume.

It is well known that one of the principal cost factors of a radio broadcast receiver is the labor cost in assembling the extremely large number of circuit elements in their appropriate places and in making bonded connections to and between such elements, usually by soldering. Numerous attempts have heretofore been made toward the design of a radio broadcast receiver in which all of the parts would be completely preformed and would have connection provisions such that a mere assembly of the several elements on the supporting chassis would complete the necessary connections without requiring any permanent bonding or soldering of auxiliary connectors to complete the circuit; that is a "solderless" receiver substantially free from bonded connections. However none of the arrangements so far proposed has met with commercial success usually because of one or more of the following factors: (1) The fabrication process was too complicated or too costly, or both, for practical use; (2) there was no practicable way for procuring simple circuit cross-over connections; and (3) certain of the circuit connections were impermanent and became noisy in operation.

It is an object of the invention, therefore, to provide a new and improved wave-signal translating apparatus chassis substantially free from bonded circuit connections which is effective to overcome one or more of the above-mentioned disadvantages and limitations on such apparatus heretofore proposed.

It is another object of the invention to provide a new and improved wave-signal translating apparatus chassis substantially free from bonded circuit connections which is relatively simple and inexpensive to fabricate and at the same time is rugged in construction.

It is another object of the invention to provide a new and improved wave-signal translating apparatus chassis of the type described incorporating simple circuit cross-over provisions.

It is another object of the invention to provide a new and improved wave-signal translating apparatus chassis of the type described in which all of the circuit connections are permanent and are quiet in operation.

In accordance with the invention, a wave-

2

signal translating apparatus chassis substantially free from bonded circuit connections comprises a pattern sheet of insulation material having a plurality of prearranged group of apertures adapted to receive plug-in devices such as vacuum tubes, circuit-element assemblies, and the like. The chassis also includes a plurality of preformed circuit connectors disposed on the sheet, each including terminal elements disposed to be received in certain of the apertures of the sheet and to engage contact elements of predetermined ones of the devices and constituting substantially the sole connections between the devices, and means for securing the connectors in place on the sheet.

15 Further in accordance with the invention, the method of fabricating a wave-signal translating apparatus chassis of the type described comprises the step of perforating a sheet of insulation material to form a plurality of prearranged groups of apertures adapted to receive plug-in devices, such as vacuum tubes, circuit element assemblies, and the like. The method also includes the steps of preforming a plurality of circuit connectors with terminal elements and constituting substantially 20 the sole connections between the devices, disposing the connectors on the sheet with their terminal elements received in certain of the apertures thereof, and securing the connectors in place on the sheet.

25 30 Further in accordance with the invention, in a wave-signal translating apparatus chassis of the type described, there is provided a cross-over unit comprising a pattern sheet of insulation material, a plurality of preformed circuit connectors disposed on the sheet, such sheet being formed with a non-linear aperture therein defining a tongue of such sheet. A first of the preformed connectors has an offset portion proportioned to underlie such tongue while the second 35 of the preformed connectors is disposed to overlie the tongue and to extend approximately normal to the first connector.

40 Further in accordance with the invention, in a wave-signal translating apparatus chassis of the type described there is included an arrangement for connecting an individual circuit element to the chassis comprising a pair of spaced apertures in the sheet, the apertures being disposed to register with two predetermined connectors and the connectors including provisions registering with the apertures for frictionally engaging circuit element connectors inserted therethrough.

45 50 For a better understanding of the invention, together with other and further objects thereof, reference is had to the following description taken

in connection with the accompanying drawings while its scope will be pointed out in the appended claims.

Referring now to the drawings, Fig. 1 is a schematic physical layout of a wave-signal translating apparatus chassis embodying the invention and utilized in a five-tube A. C.-D. C. radio broadcast receiver; Fig. 2 is a fragmentary perspective view of a portion of the chassis of Fig. 1 illustrating a circuit cross-over unit thereof; Fig. 3 is a detailed perspective view of an arrangement for connecting a circuit element such as a condenser into the chassis of Fig. 1; Fig. 4 is a view in elevation of a complete radio broadcast receiver embodying the chassis of the invention; while Fig. 5 is a schematic circuit diagram of a radio broadcast receiver corresponding to the physical layout of Fig. 1.

Referring now to Fig. 1 of the drawings, there is represented a schematic physical layout of a wave-signal translating apparatus chassis embodying the invention and substantially free from bonded connections. Specifically, the chassis represented is that of a five-tube A. C.-D. C. broadcast receiver, although it will be understood that the invention is equally applicable to chassis of other wave-signal translating apparatus or to sub-assemblies or sub-chassis thereof, and the term "chassis" as used herein and in the appended claims is intended to refer to any of such chassis, sub-chassis or sub-assembly.

The chassis of Fig. 1 comprises a pattern sheet 10 of insulation material, such as a thermoplastic or thermosetting resin, having a plurality of pre-arranged groups of apertures 11-18, inc. Each of these groups of apertures is adapted to receive a plug-in device; for example, the groups 11, 13, 15, 16 and 17 are adapted to receive respectively a type 12SA7 oscillator-modulator tube, a type 12SK7 intermediate-frequency amplifier tube, a type 12SQ7 detector and first audio amplifier, a type 50L6 beam-power audio-frequency amplifier, and a type 35Z5 rectifier, while the groups 12 and 14 are adapted to receive intermediate-frequency selectors 19 and 20, respectively, and the group 18 is adapted to receive the local oscillator coil assembly 21.

The chassis also includes a plurality of pre-formed strip-like circuit connectors, such as connectors 22-29, inc., comprising interconnections for the plug-in devices and the connectors 30 and 31 comprising the +B and -B power supply buses, respectively. There are also a group of similar pre-formed connectors, such as the connectors 32-38, inc., for making connection between the several plug-in devices and the external circuits of the chassis. All of the connectors 22-38, inc., described are disposed on the top side of the pattern sheet 10, as viewed in Fig. 1, while there is also provided a preformed connector 39 disposed on the opposite side of the pattern sheet 10 and constituting the ground or reference potential bus of the chassis.

As shown more clearly in Fig. 2, each of the connectors, such as connectors 40 and 41, includes one or more terminal elements, such as the terminal elements 40a and 41a, disposed to be received in certain of the apertures of the pattern sheet 10; in the case of the terminal elements 40a and 41a, to engage two of the apertures of the group 18 into which the oscillator coil assembly is to be plugged. As shown in Fig. 2, each of the terminal elements 40a, 41a comprises an elongated resilient contact clip ex-

tending from its respective preformed connector and through its respective aperture in the pattern sheet 10. Preferably, the preformed connectors of the type described constitute substantially the sole connections or the entire connections between the several plug-in devices, such as the vacuum tubes described and the plug-in units 19, 20 and 21, and to all external circuits to the chassis.

The chassis of Fig. 1 also includes a plurality of circuit cross-over units or arrangements for the connectors. These may be identified as the circuit cross-overs 42-48a, inc. Each of these cross-over units may be either single or double, by way of example the double cross-over 42 being represented in detail in Fig. 2. As shown in this figure, the cross-over 42 comprises a U-shaped aperture 42a punched or otherwise formed in the pattern sheet 10 and a first preformed connector, for example the -B bus 31, having an offset portion 31a proportioned and disposed to underlie the tongue 42b between the arms of the U-shaped aperture 42a. The cross-over connectors 40 and 41 are disposed to overlie the tongue 42b and to extend approximately parallel thereto and approximately normal to the connector 31. In this fashion, it is seen that the cross-over connectors 31, 40 and 41 are completely insulated from each other and at the same time permanently retained out of contact with each other.

The chassis of Fig. 1 also includes a plurality of arrangements for connecting individual circuit elements to the chassis, such as resistors R₁-R₆, inc., and the condensers C₁-C₇, inc. For example, one such arrangement is shown in Fig. 3 illustrating the connection of the condenser C₃ to the preformed connectors 31 and 34. As illustrated in Fig. 3, the pattern sheet 10 is provided with a pair of spaced apertures 49a and 49b spaced to register with the connectors 31 and 34, respectively. The connectors 31 and 34 include provisions registering with the apertures 49a and 49b, respectively, for frictionally engaging the circuit element connectors or lead wires 50a, 50b, respectively, of the condenser C₃. For example, the connector 34 is formed with a small diamond-shaped aperture 34a having a pair of opposed peripheral fingers 34b. The connector elements are preferably of resilient material such as Phosphor bronze and the fingers, such as the fingers 34b, are offset from the plane of the connector so that they resiliently grip the circuit element connector 50b inserted through the apertures 34a and 49b. This arrangement for connecting individual circuit elements merely by inserting or plugging them into appropriately spaced apertures in the several connectors is representative of the manner of connection of the resistors R₁-R₆, inc., and the condensers are C₁-C₇, inc. It has been found that, with the construction illustrated, a permanent and quiet electrical connection is established between the circuit element connectors, such as the connectors 50a, 50b of condenser C₃, and the pre-formed chassis connectors and that this engagement is sufficiently strong that if it is attempted to remove the circuit elements, such as the condenser C₃, the connectors 50a, 50b may be torn from the circuit element or broken or, in some cases, the connection with the preformed chassis connectors permanently deformed.

The chassis of Fig. 1 also incorporates means for securing the several preformed circuit connectors 22-38, inc., in place on the pattern sheet

18. This may be done in any convenient manner as by riveting, gluing, or the like, but is preferably effected, as shown, by placing over the sheet 10 a second perforated pattern sheet 51 (Figs. 2 and 3) of insulation material having apertures registering with the apertures of the pattern sheet 10 and with the preformed circuit connectors disposed between the sheets 10 and 51, except the ground or reference potential bus 38 which is disposed on the opposite side of the sheet 10 and secured thereto in any suitable manner. The sheets 10 and 51 are secured together by screws, bolts, rivets, or the like, not shown.

The chassis of Fig. 1 is also adapted to be connected to other elements of a radio broadcast receiver not forming a part of the chassis per se. For example, the circuit connectors 32 and 34 are provided with terminals 32a and 34c, respectively, adapted to be connected to an external loop or antenna ground circuit. Similarly, the connectors 37 and 38 are provided with terminals 37a and 38a, respectively, which are adapted to be bridged by the back cover of the receiver carrying the loop, as described herein-after, in order to open the power circuit to the chassis when the cover is removed and the various circuit elements of high potential are exposed. Further there is provided a separate volume control unit 52 having a conventional flexible connector 52c to the -B bus 31. Also the receiver includes a sound reproducer or loud speaker 53 having an operating mechanism 53a which is connected to preformed connectors 54 and 55 constituting additional ground connectors and disposed on the opposite side of the pattern sheet 51. The speaker operating mechanism 53a is also provided with an external connection plug 53b having the connection prongs indicated as SP, S+B and SF and adapted to be connected to a conventional socket 53c having connections to points correspondingly identified on the chassis. The receiver is also provided with an electrolytic filter condenser C₈ connected by conventional leads 56, 57 and 58 to the circuit connectors 36, 39 and 31, respectively. Power for the receiver chassis is derived from an ordinary commercial power circuit by means of a removable plug 59 having leads 60 and 61 connected to the bus connector 31 and to the connector 38, respectively.

In the fabrication of the wave-signal translating apparatus chassis of Fig. 1 described above, the pattern sheet 10 of insulation material is perforated with registering groups of apertures 11-18, inc., for the plug-in vacuum tubes and selector and oscillator-coil assemblies and with a plurality of pairs of spaced apertures, such as the apertures 49a, 49b, for receiving the individual circuit elements such as the condensers C₁-C₇, inc., and the resistors R₁-R₈, inc. The sheet 51 is also perforated with groups and pairs of apertures registering with those of pattern sheet 10, one such aperture 51a being shown in Fig. 3. The pattern sheet 10 is also punched or stamped to provide a plurality of U-shaped apertures, such as the aperture 42a, to permit the formation of the cross-over units 42-48a, inc.

The chassis circuit connectors, such as the connectors 22-38, inc., are then stamped or otherwise formed from strip or sheet material, preferably of a resilient spring metal such as Phosphor bronze. Portions of the preformed connectors are formed into elongated resilient contact clips, such as the clips 40a, 41a of Fig. 2, extending therefrom substantially normal to the plane of the connectors and at predetermined spaced

points disposed to engage appropriate ones of the groups of apertures 11-18, inc. In predetermined ones of the circuit connectors 22-38, inc., to which individual circuit elements are to be attached, there are formed in pairs provisions for frictionally engaging the individual circuit element connectors when inserted through the pairs of apertures formed in the sheets 10 and 51 registering therewith. The frictional engaging provisions may be of the form illustrated in Fig. 3 and described above. The connectors 22-38, inc., are thereupon disposed on one side of the pattern sheet 10 with their terminal elements or clips, such as the clips 40a, 41a, received in and extending through their corresponding apertures in the sheet 10. The preformed ground connector 38 is disposed on the opposite side of the pattern sheet 10 and secured thereto in any suitable fashion while the ground connectors 54 and 55 are disposed on the inner side of the sheet 51 and secured thereto.

Each of the U-shaped apertures, such as the apertures 42a, is located at one of the circuit cross-over points of two of the preformed connectors 22-38, inc., to form the cross-over units 42-48a, inc. To this end, such of the circuit connectors as are involved in the circuit cross-over have a portion thereof offset, such as the offset portion 31a (Fig. 2) of connector 31, to underlie the tongue of the associated aperture in the sheet 10, while the crossing connector or connectors are disposed and arranged to overlie the tongue and extend approximately normal to the underlying connector.

Thereupon the several connectors are secured in place. This may be effected in any convenient manner but preferably and as illustrated by juxtaposing the pattern sheet 51 upon the pattern sheet 10 with their apertures in register and securing them together by any suitable means such as screws, rivets, or the like, (not shown) to retain the circuit connectors in place.

In Fig. 4 is illustrated a view in elevation, partly in section, of a complete radio broadcast receiver incorporating the chassis apparatus of the invention. This receiver comprises an enclosing cabinet or housing 60 with the chassis comprising the pattern sheets 10 and 51 mounted vertically therein and extending substantially across the inside of the cabinet. The various vacuum tubes, such as the tube 61, and the various coil assemblies, such as the oscillator assembly 21, are plugged in to the chassis of the set and extend horizontally therefrom. Also secured to the chassis by screws, bolts, rivets, or the like, is the volume control unit 52 provided with a manually operable adjusting knob 52a mounted on a shaft 52b extending through the front of the cabinet. The loud speaker 53 is also secured to the chassis sheets 50 and 51 by means of screws or bolts 53b which also engage the ground or reference potential buses 54, 55, thereby grounding the unit. The tuning condensers are likewise secured to and supported from the chassis sheets 10 and 51 and are provided with a tuning knob 62 secured to a shaft 62a extending through the front of the cabinet 60 and connected to adjust the tuning condensers through gearing 62b. The back of the cabinet 60 is closed by a panel member 63 spaced from the chassis sheets 10 and 51 by suitable posts 64 having pins 64a engaging the terminal contacts 32a and 34a. A receiving loop antenna 65 is mounted on the back plate 63, while this plate also carries a bridging contact (not shown) for the power sup-

ply terminals 37a and 38a of Fig. 1 to ensure that the receiver chassis is de-energized whenever the back plate 63 is removed.

In Fig. 5 there is represented a schematic circuit diagram of the five-tube A. C.-D. C. receiver represented in the schematic physical layout of Fig. 1, corresponding circuit elements and components being represented by the same reference numerals. Since the receiver circuit illustrated is an entirely conventional five-tube A. C.-D. C. superheterodyne receiver, the operation of which is well understood in the art, it is believed that an explanation of such operation is unnecessary herein. While the invention has been illustrated and described as applied to a conventional five-tube A. C.-D. C. superheterodyne-broadcast receiver, it is to be understood that this embodiment is purely illustrative and that the chassis of the invention is applicable generally to chassis of wave-signal translating apparatus, including receivers and transmitters, comprising either the complete chassis of the wave-signal translating apparatus or a sub-chassis or sub-assembly thereof.

While there has been described what is at present considered to be the preferred embodiment of the invention, it will be apparent to those skilled in the art that various changes and modifications may be made therein without departing from the spirit or scope of the invention.

What is claimed as new is:

1. A chassis for supporting and interconnecting electrical devices of the plug-in type, said chassis comprising a flat sheet of insulating material having apertures arranged to conform with a predetermined pattern for receiving the plug portions of the electrical devices, a plurality of rigid strip conductors respectively extending between predetermined ones of said apertures, and holding means for securing said conductors to said insulating sheet, said conductors having integral spring contact clips respectively positioned in certain of said apertures in said sheet for directly receiving the plug portions and affording unbonded electrical connections therewith, said insulating sheet having at least one non-linear slot therein defining a tongue thereof, a first one of said conductors having an offset portion of such configuration to be transversely insertable in said slot to underlie said tongue, another one of said conductors being disposed to overlie said tongue and extend approximately normal to said first conductor, whereby said tongue extends between such conductors to insulate them one from the other, said spring contact clips and said offset portion of said con-

ductors cooperating with said apertures and said slot in said sheet to position said conductors on said insulating sheet.

2. A chassis for supporting and interconnecting electrical devices of the plug-in type, said chassis comprising a first flat sheet of insulating material having apertures arranged to conform with a predetermined pattern for receiving the plug portions of all said devices, a plurality of rigid strip conductors respectively extending between predetermined ones of said apertures, and a second insulating sheet secured to the first insulating sheet with said conductors being disposed between said sheets, said conductors having integral spring contact clips at the ends thereof respectively received in certain of said apertures in said sheets for directly receiving the plug portions and affording unbonded connections therewith, whereby said conductors constitute the sole electrical connections between the electrical devices, said first sheet having a plurality of U-shaped slots therein each defining an insulating tongue thereof, certain of said conductors having preformed offset portions of such configuration to be transversely insertable in said slots to underlie said tongues, said spring contact clips and said offset portions of said conductors cooperating with said apertures and said slots to position said conductors on said first insulating sheet, others of said conductors being respectively disposed to overlie said tongues to provide insulated cross-overs between said conductors.
